UNITED STATES PATENT OFFICE

2,199,245

REFRIGERATOR

Delbert F. Newman, Schenectady, N. Y., assignor
to General Electric Company, a corporation of
New York

Application April 22, 1939, Serial No. 269,432

8 Claims. (Cl. 62—89)

My invention relates to refrigerators and more particularly to refrigerators having cooling units provided with a receptacle thereunder.

Under high humidity conditions I have found that due to the size and relatively low conductivity of receptacles such as the conventional drip tray or meat pan placed below the cooling unit, the receptacle tends to assume a relatively low temperature due to its proximity to the cooling unit, especially during defrosting periods when the ice on the cooling unit melts into the drip pan. As a result, air contacting the under surface of the receptacle is cooled below the dew point and therefore condenses on the receptacle. This condensation may drip onto the articles stored in the refrigerator. It is therefore an object of my invention to provide a new and improved means for preventing condensation on the under surface of the drip tray or other receptacle disposed below the cooling unit in a refrigerator.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawing in which Fig. 1 is a fragmentary front elevational view of a household refrigerator embodying the principles of my invention; and Fig. 2 is an enlarged perspective view, partly in section, of the shield shown in Fig. 1.

I have shown a household refrigerator 10 provided with heat insulated walls defining a refrigerated food storage compartment 11 provided with an opening 12 in the front wall thereof and a heat insulated door 13 for the opening 12. The refrigerator 10 is cooled by a refrigerating machine including a cooling unit or evaporator 14 arranged in the upper portion of the refrigerated compartment 11. The remaining portions of the refrigerating circuit have not been illustrated in the drawing and any suitable arrangement may be used. A plurality of shelves 15, one of which is illustrated in the drawing, may be suitably supported in the refrigerator 10. As shown in Fig. 1, a receptacle illustrated in the form of a drip tray 16 is located below the evaporator or cooling unit 14 to receive the drip water from the unit 14. In order to minimize the area of the drip tray subjected to contact with the circulating box air and to eliminate the collection of moisture thereon, I have provided shielding means 17.

As illustrated in Fig. 2, the shielding means or baffle 17 comprises two spaced-apart sheet-like members 18 and 19 maintained in spaced-apart relationship by means formed of relatively poor heat conducting material such as a continuous non-heat conducting gasket 20 extending around the periphery of the baffle 17. The members 18 and 19 may be formed of any suitable material but I prefer to use metallic plates, such as aluminum.

In the refrigerator 10, the air in the refrigerated compartment 11 is usually maintained at a temperature of approximately 40° F. by circulating currents of air set up in the refrigerated compartment 11 by the cooling unit 14. In order to prevent the formation of moisture on the lower plate 18, which is remote from the cooling unit 14, of the baffle or shield 17, it is desirable to provide the surface of plate 18 directed away from the cooling unit 14 with a surface which absorbs radiant heat in order that the lower plate 18 may readily acquire substantially the same temperature as the box air. This result is preferably obtained by anodizing the exterior surface of the shield member 18 although any other suitable surface may be used as enamel, for example. In some instances it is preferable to minimize the emission of heat from the shield 17 to the drip tray 16 and evaporator 14 as by providing shield member 19 with an upper or exterior surface having a low coefficient of emission of radiant heat. This result may be accomplished by polishing the outside surface of plate 19. I have found in most cases, however, that it is not necessary to polish the upper surface of plate 19 so that, if desired, an unpolished sheet may be used or the plate 19 may be finished in the same manner as plate 18.

The continuous gasket 20 is made of any suitable resilient non-heat-conducting material, preferably rubber, and in the form illustrated in Fig. 2 is provided with two longitudinally extending spaced-apart grooves 21 and 22 for receiving the edges of plates 18 and 19, respectively. With this arrangement, a dead air space is provided within the shield 17 which minimizes the transfer of heat between plates 18 and 19.

If the sheets 18 and 19 are composed of relatively thin sheets it may be necessary to provide spacers of relatively non-heat-conducting material, as indicated by the numeral 23, to prevent bending of the sheets with respect to each other when subjected to the weight of the drip tray 16.

While I have shown shield 17 resting on the shelf 15 and supporting drip tray 16, other modi-

fications will occur to those skilled in the art. For example, it is not necessary that the exterior surface of shield member 19 contact the bottom wall of the drip tray 16 so that if desired, the drip tray 16 may be supported by a shelf 15 in the conventional manner while shield 17 may be supported below the shelf 15 and drip tray 16 in any suitable manner, as by hooks engaging shelf 15, for instance. However, the shield 17 should be adjacent the drip tray 16 so that the space between the bottom wall of the drip tray 16 and shield 17 will not be large enough to permit a substantial circulation of air therebetween.

While I have shown a particular embodiment of my invention I do not desire to be limited to the particular construction shown and described and I intend in the appended claims to cover all modifications within the spirit and scope of my invention.

20. What I claim as new and desire to secure by Letters Patent of the United States, is—

1. In a refrigerator having a plurality of walls defining a food storage compartment, a cooling unit and a receptacle therein, a shield arranged beneath said receptacle and adjacent thereto, said shield comprising a plurality of members maintained in spaced-apart relationship by means of a peripheral sealing element, the surface of the member of the shield most remote from said cooling unit which is directed away from said cooling unit having a relatively high coefficient of absorption of radiant heat.

2. In a refrigerator having a plurality of walls defining a food storage compartment, a cooling unit and a receptacle therein, a shield arranged beneath said receptacle and adjacent thereto, said shield comprising a plurality of members maintained in spaced-apart relationship by means of a peripheral sealing element, the surface of the member of the shield most remote from said cooling unit which is directed away from said cooling unit having a relatively high coefficient of absorption of radiant heat, and the surface of the member presented to said receptacle having a relatively low coefficient of emission of radiant heat.

3. In a refrigerator having a food compartment and a cooling unit and receptacle therein, a shield in said compartment arranged beneath said receptacle and adjacent thereto, said shield comprising a plurality of members maintained in spaced-apart relationship by means of a peripheral sealing element, the exterior surfaces of said shield having relatively high coefficients of absorption of radiant heat.

4. In a refrigerator having a food compartment, and a cooling unit and a receptacle therein, a shield below said cooling unit and supporting said receptacle, said shield comprising a plurality of members maintained in spaced-apart

relationship by means of a continuous resilient non-heat-conducting sealing element, said element having a plurality of longitudinally extending spaced-apart grooves for engaging said members. 5

5. In a refrigerator having a food compartment, and a cooling unit and a receptacle therein, a shield located below said cooling unit and supporting said receptacle, said shield comprising a plurality of members maintained in spaced-apart relationship by means of a continuous resilient non-heat-conducting sealing element, said element having a plurality of longitudinally extending spaced-apart grooves for engaging said members, the surface of the member of the shield 15 most remote from said receptacle which is directed away from said receptacle having a relatively high coefficient of absorption of radiant heat.

6. In a refrigerator having a food compartment and a cooling unit, a receptacle therein, a shield located below said cooling unit and arranged to support said receptacle, said shield comprising a plurality of members maintained in spaced-apart relationship by means of a continuous resilient non-heat-conducting sealing element, said element having a plurality of longitudinally extending spaced-apart grooves for engaging said members, the surface of the member of the shield most remote from said receptacle which is directed away from said receptacle having a relatively high coefficient of absorption of radiant heat, and the surface of the member presented to said receptacle having a relatively low coefficient of emission of radiant 35 heat.

7. A shield member for use in a refrigerator having a food compartment and a cooling unit and a receptacle therein, comprising a plurality of members maintained in spaced-apart relationship by means of a continuous resilient non-heat-conducting sealing element, said element having a plurality of longitudinally extending spaced-apart grooves for engaging said members, an exterior surface of said shield having a relatively high coefficient of absorption of radiant heat. 40

8. In a refrigerator having a plurality of walls defining a food storage compartment, a cooling unit and a receptacle therein, a shield arranged beneath said receptacle and adjacent thereto, said shield comprising a plurality of spaced-apart members, means formed from material of relatively low heat conducting characteristics maintaining said members in spaced-apart relationship, the surface of said shield directed away from said cooling unit having a relatively high coefficient of absorption of radiant heat. 55
